MAGNETIC SWITCH

Harvey Hubbell, Long Hill, Conn.

Application March 19, 1942, Serial No. 435,375

9 Claims. (Cl. 200—87)

This invention relates to electric switches and particularly a magnetically operated switch, and has for an object to provide a construction in which the operating effort is reduced to a minimum. A particular object is to provide a construction of switch using a magnetic operating means, in which as the magnetic operating means is moved to and from a position to shift the movable armature the magnetic or flux circuit is shifted between the movable armature and a stationary armature, so that the pull of the movable armature on the magnet as the magnet moves away from it is reduced to a minimum, thus reducing to a minimum the resistance to shifting of the magnet and reducing the effort required for this operation.

With the foregoing and other objects in view I have devised a construction two embodiments of which are shown by way of example in the accompanying drawings forming a part of this specification. It is, however, to be understood the invention is not limited to the specific constructions and arrangements shown but may employ various changes and modifications within the scope of the invention.

In these drawings:

Fig. 1 is a longitudinal section through one form of the device showing the switch in closed position, certain elements being shown in elevation;

Fig. 2 is a section substantially on the line 2—2 of Fig. 1;

Fig. 3 is a transverse section substantially on the line 3—3 of Fig. 1;

Fig. 4 is a partial section and partial elevation of the main elements of the switch similar to Fig. 1 but showing the movable parts with the switch in the open position;

Fig. 5 is a section showing a modified construction with the switch in closed position;

Fig. 6 is a transverse section substantially on the line 6—6 of Fig. 5, and

Fig. 7 is a similar section but showing the switch in the open or off position.

Referring first to Figs. 1 to 4, the switch illustrated comprises a base 10 of insulating material on which is mounted the movable switch element 11, in this case a flat spring, mounted on a suitable support, as a metal conducting post 12 mounted in the base 10, this spring element being secured thereto by any suitable means, such as a screw 13. The post extends through the base 10 and connects with a strap 14 on which is a binding screw 15 for connection of a lead wire 16.

The member 11 carries a contact element 17 and an armature 18 which in this case is a flat strip of soft iron. A stationary contact 19 to cooperate with the contact 17 is mounted on a bracket 20 secured to the base 10 by any suitable means, such as a rivet 21 which also mounts on the base a strap 22 carrying a binding screw 23 for connection of the lead 24. The contact 9 is adjustable in the bracket, and in this case comprises a screw as shown.

A second support or bracket 25 is mounted on the base by any suitable means such as the screws 26, and carries a bearing 27 for a short shaft 28 mounted on the lower end of which is a substantially U-shaped magnet 29 having the spaced pole pieces 30 located slightly above the armature 18 so that there is a clearance space between them. This shaft 28 may be operated by any suitable means to turn or oscillate it, as for example by a handle 31. By turning this shaft the magnet is turned to carry the poles 30 to and from a position over the armature 18 and a position adjacent thereto, as shown in the full and dotted lines Figs. 1, 2 and 3, the dotted lines of 25 Fig. 2 and the full lines of Fig. 4 showing the magnet in position to release the armature 18 and permit the resiliency of the spring 11 to shift the contact 17 away from the contact 19, as shown in Fig. 4, to break or open the circuit.

Laterally to one side of the armature 18 is a stationary armature 32 in this case comprising the two arc-shaped elements 33, one located on each of the opposite sides of the armature 18, so that when the magnet 29 is rotated to carry the poles 30 from the armature 18 they will pass over the stationary armature members 33. The members 33 may be secured to the base by any suitable means such for example as lugs 33a passing through the base and bent over on the under side. There is also a slight clearance between the poles 30 and the armature elements 33, about the same as that between these poles and the armature 18, so that the armatures will not freeze to the magnet and there will be no friction between them. When the magnet 29 is turned so that its poles are over the armature 18 the magnetic or flux circuit is through the magnet and the armature 18. Therefore the armature is attracted toward the magnet and it is shifted against the action of the spring 11 to carry the contact 17 into engagement with the contact 19 to close the circuit. When the magnet is turned to carry its poles away from their position over the armature 18, as indicated in dotted lines in Fig. 2, they move over the members 33

of the stationary armature 32 and the magnetic or flux circuit is through the magnet and the armature 32, thus relieving the attraction of the magnet on the armature 18, permitting the spring 11 to shift the contact 17 away from the contact 19 to open the circuit, as indicated in Fig. 4. As in this position the flux is transferred from the movable armature to the stationary armature there is no pull of the movable armature on the magnet to resist this movement, and therefore the only force required to turn the magnet is that of the friction of the shaft 28 in its bearing. Furthermore, the movement required of the magnet from the position attracting the armature 18 to a position releasing this armature is very small, so only slight movements of the magnet are required between the on and off positions of the switch. In operating the switch the magnet may be entirely rotated or merely oscillated or reciprocated, depending on the use and application in which it is employed.

The parts may be enclosed by a suitable cover or casing C.

Another arrangement is shown by way of example in Figs. 5 to 7. In this case the spring contact is the same as in Figs. 1 to 4 but the operating magnet 34 corresponding to the magnet 29 is mounted differently. In this case it is mounted on a support 35 pivoted on a short shaft or stud 36 mounted in a supporting bracket 37 secured to the base 10 by any suitable means, such as a rivet 38. The support 35 includes an operating means such as a handle 39. It will be seen that with this arrangement oscillation of the support 35 on its pivot 36 will shift the magnet 34 and its poles 30 back and forth across the armature 18, and when they are over this armature the magnetic or flux circuit is through the magnet 34 and the armature 18 causing the armature to be attracted by the magnet and shifted to carry the contact 17 into engagement with the contact 19 to close the circuit. When the magnet is shifted away from the armature it is released so that the spring carries the contact 17 away from the contact 19 to open the circuit as indicated in dotted lines Fig. 5.

On opposite sides of the armature 18 are mounted stationary armature members 40, there being one on each side of the armature 18 if the magnet is mounted to be swung in either direction from the armature 18. If it is intended to be swung in one direction only, then only one armature member 40 will be required. As the magnet is mounted to swing about the center of the pivot 36 the free ends 41 of the poles 30 swing in an arc of a circle. It is therefore preferred to curve the ends of these poles on an arc with the pivot as the center and also to correspondingly curve the faces 42 of the armature members 40 so that the faces of the poles move substantially parallel to the faces of the armature, although of course this arrangement is not absolutely necessary. The armature members 40 may be secured to the base by any suitable means such for example as the lugs 43 extending through and bent over on the underside of the base.

The operation in this case is the same as that in the first form shown. When the poles of the magnet are over the armature 18, as shown in Figs. 5 and 6, the magnetic or flux circuit is through the magnet and the armature 18, thus causing the magnet to attract the armature and shift it against the action of the spring 11 to bring the contact 17 into engagement with the

contact 19 to close the circuit. If the magnet is swung laterally to carry its poles from over the armature 18 to a position over one of the armature members 40, as indicated in Fig. 7, the magnetic or flux circuit is transferred from the armature 18 to the corresponding armature member 40 so that it is now through this armature member and the magnet, which releases the attraction of the magnet on the armature 18 permitting the spring 11 to shift the contact 17 away from the contact 19 to open the circuit. Here again as in the first form, as the magnetic or flux circuit is transferred from the movable armature to the stationary armature there is no pull of the movable armature on the magnet to resist its swinging movement, so that the only resistance to movement of the magnet is that within the pivotal bearing 38 or any other operating means that may be employed. Also the movement of the magnet from a position attracting the armature 18 to one releasing it is very small so that very little shifting of the magnet is required to open and close the switch. There also is a slight clearance maintained between the poles of the magnet 34 and the armatures 18 and 42 to eliminate friction and prevent freezing of the armature to the magnet.

It is to be understood that the arrangements shown and described are illustrated merely by way of example and that any of numerous different arrangements may be used and any of numerous operating means for the movable magnet may be employed, such for example as any of the well known switch operating devices, as push-off buttons, kick-off devices, and so forth.

Having thus set forth the nature of my invention, what I claim is:

1. An electric switch comprising a movable contact, an armature connected therewith, a magnet mounted for movement to and from a position over the armature to shift and release it to operate the contact, and a stationary armature at one side of the first armature over which the magnet moves as it is shifted from the first armature, both armatures being always spaced from the magnet.

2. In an electric switch, a movable contact, a movable armature for shifting the contact, a magnet movable to and from a position adjacent the armature to attract and release it, and a second armature arranged so that as the magnet moves from the first armature it approaches the second to transfer the magnetic field from the first to the second armature, both armatures being always spaced from the magnet.

3. An electric switch comprising a spring support, a movable contact carried by said support, an armature on the support, a magnet mounted for movement to a position adjacent the armature to attract it to shift the contact, and a second armature adjacent the first and toward which the magnet moves as it leaves the first armature to transfer its flux to the second armature, both armatures being always spaced from the magnet.

4. An electric switch comprising a movable contact, an armature connected therewith for shifting it, a substantially U-shaped magnet mounted so that its poles are movable to and from a position over the armature to shift it, and a second armature adjacent the first armature over which the poles of the magnet move as they are shifted from the first armature, both armatures being always spaced from the magnet.

5. An electric switch comprising a spring contact support, an armature mounted on said support, a substantially U-shaped magnet movable to and from a position with its poles over the armature to shift the armature and support against the action of the spring, and a second armature adjacent the first armature over which the poles move as they leave the first armature, both armatures being always spaced from the magnet.

6. An electric switch comprising a movable contact, an armature connected therewith, a substantially U-shaped magnet having spaced poles and mounted to turn about an axis extending longitudinally of the poles, said poles movable to a position closely over the armature during its turning movement to shift the armature, other armature means laterally of the first armature over which the poles move during other parts of their turning movement to release the first armature, both armatures being always spaced from the magnet, and means for turning the magnet.

7. An electric switch comprising a movable contact, an armature connected therewith, a magnet having spaced poles mounted to move

to and from a position over the armature to shift the armature, other armature means laterally of the first armature over which the poles move as they leave the first armature to release it, both armatures being always spaced from the magnet, and means for shifting the magnet.

8. An electric switch comprising a movable contact, an armature connected therewith, a magnet having spaced poles mounted to swing laterally to and from a position over the armature to shift it, another armature at one side of the first armature over which the poles move as they leave the first armature to release it, both armatures being always spaced from the magnet, and means for shifting the magnet.

9. In a device of the character described, a movable armature, a magnet mounted for movement to and from a position adjacent the armature to shift and release it, armature means laterally of the first armature over which the magnet moves as it leaves the first armature to release it, both armatures being always spaced from the magnet, and means for shifting the magnet.
